US00D767523S

(12) **United States Design Patent** (10) **Patent No.:** **US D767,523 S**
(45) **Date of Patent:** **** Sep. 27, 2016**

(54) **MOBILE PHONE**

(71) Applicants: **Hisense Mobile Communications Technology Co., Ltd.**, Qingdao, Shandong (CN); **HISENSE USA CORP.**, Suwanee, GA (US)

(72) Inventor: **Zhen Zhang**, Qingdao (CN)

(73) Assignees: **Hisense Mobile Communications Technology Co., Ltd.**, Qingdao, Shandong (CN); **Hisense USA Corp.**, Suwanee, GA (US); **Hisense International Co., Ltd.**, Qingdao (CN)

(**) Term: **14 Years**

(21) Appl. No.: **29/504,339**

(22) Filed: **Oct. 3, 2014**

(51) LOC (10) Cl. **14-03**

(52) U.S. Cl.

USPC ..... **D14/138 G**

(58) **Field of Classification Search**

USPC .. D14/138 G, 138 AD, 248, 138 R, 138 AC, D14/247, 137, 341-347

(57) **CLAIM**

The ornamental design for a mobile phone, as shown and described.

DESCRIPTION

FIG. 1 is a front view of the mobile phone according to the new design;

FIG. 2 is a top view of the mobile phone;

FIG. 3 is a bottom view of the mobile phone;

FIG. 4 is a right side view of the mobile phone;

FIG. 5 is a left side view of the mobile phone;

FIG. 6 is a back view of the mobile phone;

FIG. 7 is a front perspective view of the mobile phone; and,

FIG. 8 is a back perspective view of the mobile phone.

The broken lines that are immediately adjacent to the claim, and define unshaded regions, represent the bounds of the claim while all other broken lines are directed to environment; the broken lines form no part of the claimed design.

1 Claim, 6 Drawing Sheets
